UNITED STATES PATENT OFFICE.

THOMAS H. KENNEDY, OF ALTA LOMA, TEXAS.

HEATER.

Application filed February 16, 1926. Serial No. 88,533.

This invention relates to new and useful improvements in a heater.

One object of the invention is to provide a heater of the character described specially 5 designed to utilize oil as a fuel.

Another object of the invention is to provide a heater of the character described capable of adjustment so as to utilize crude or refined oil as fuel.

10 A further feature of the invention is to provide a heater equipped with means for readily regulating the draft.

The invention also comprehends a novel 15 form of fuel tank specially designed for use in combination with the heater.

With the above and other objects in view this invention has particular relation to certain novel features of construction, operation and arrangement of parts, an example 20 of which is given in this specification and illustrated in the accompanying drawings, wherein:—

Figure 1 shows a vertical sectional view.

25 Figure 2 shows a cross sectional view taken on the line 2—2 of Figure 1.

Figure 3 shows a plan view of the heater, and

30 Figure 4 shows a side elevation of the heater, shown in combination with the fuel tank.

Referring now more particularly to the drawings wherein like numerals of reference designate similar parts in each of the figures the numeral 1 designates the heater 35 jacket, which has the bottom 2, lined with asbestos 3, and which also has the top 4, preferably bolted to the body of the jacket. The jacket is preferably formed of cast metal.

40 Within the jacket there is a bowl 5, having the supporting legs 6 which rest on the lining 3 and are bolted to the bottom of the jacket by the bolts 7. This bowl has a central upstanding conical shaped nozzle 8, which has an axial fuel passageway 9 therethrough, and a supply pipe 10 leads from the fuel tank 11 and has its discharge end threaded through the bottom of the jacket 45 and up into said nozzle 8.

50 The flow of fuel through this line to the nozzle may be controlled through the needle valve 12, with which the line is equipped, and the fuel line also has a relief cock 13 to relieve the line of any air that may become entrapped therein.

The cover 4 has a central depending draft

flue 15, whose upper end is open and whose lower end is contracted and surrounds the upper end of the nozzle 8. Fastened to the upper end of the flue there is a transverse 60 anchor bar 16. There is a disc like flame spreader 17 spaced above the nozzle. This flame spreader is attached to the lower end of the rod 18 whose upper end is threaded through the bar 16 and has a knurled hand 65 grip by means of which the rod 18 may be turned and the spreader 17 thus adjusted toward and from the nozzle. A wing nut 19 is threaded on the rod 18 above the bar 16 by means of which the rod may be locked 70 in any desired position.

The flame spreader 17 requires different 75 adjustments relative to the nozzle 8 for different grades of fuel used.

The jacket has an opening in front of the bowl 5 which may be opened and closed by the door 21 thus providing for access to the nozzle for lighting purposes and this door has the usual draft damper 22.

When the fuel is burning and the damper 80 22 closed the draft will all be down through the flue 15. The blaze will strike the spreader 17 and be spread thereby and will be carried down around the lower end of the flue and will pass up around it into the 85 jacket chamber 23. The draft through the flue 15 may be controlled, to a large degree through the damper 22. By opening this damper the draft through the flue 15 may be decreased and vice versa.

90 The fumes will pass out through the usual flue pipe 24 leading out from the upper part of the jacket.

The fuel tank is fastened to a flat wall plate 25, forming the back side thereof and 95 which has the ears 26, 26, by means of which the tank may be suspended. The water and sediment will settle to the bottom of the tank which is provided with a drain cock 27 through which they may be drained 100 off. The pipe 11 is connected into the tank some distance above its bottom so that none of the settling or water will pass through said pipe and while filling the tank the pipe 10 may be closed by the needle valve 28 with 105 which its upper end is equipped.

110 The tank cover has the air inlets 29 through which air is admitted into the tank to permit the feeding of the fuel therefrom, through the pipe 10.

What I claim is:

1. A heater including a jacket, an up-

- standing nozzle in the bottom thereof, a flue depending from the top of the jacket whose ends are open and whose lower end is disposed around said nozzle, a transverse anchor 5 bar across the upper end of said flue, a flame spreader in the flue above said nozzle and a rod adjustably connected to said bar and to the lower end of which said spreader is attached.
- 10 2. A heater including a jacket, a bowl in the bottom thereof having an upstanding nozzle, means for supplying fuel to said nozzle, a flue depending from the top of the jacket whose ends are open and whose lower 15 end surrounds said nozzle, an anchor bar across said flue, a rod adjustably connected with said bar, a flame spreader in the flue attached to said rod, said jacket having an

opening in front of the nozzle and a door for closing said opening.

3. A heater including a jacket, a bowl in the bottom thereof having an upstanding nozzle, means for supplying fuel to said nozzle, a flue depending from the top of the jacket whose ends are open and whose lower 25 end surrounds said nozzle, an anchor bar across the flue, a flame spreader in the flue and adjustably connected to said bar, said jacket having an opening, a door for closing said opening a draft controlling damper carried by said door, and a flue pipe leading out from the upper part of the jacket.

In testimony whereof I have signed my name to this specification.

THOMAS H. KENNEDY.
